Attorneys.

UNITED STATES PATENT OFFICE

THOMAS WARDLEY, OF GREENFORD, ENGLAND, ASSIGNOR TO HARTFORD-EMPIRE COMPANY, OF HARTFORD, CONNECTICUT, A CORPORATION OF DELAWARE

METHOD OF AND APPARATUS FOR ANNEALING GLASSWARE

Application filed December 17, 1930, Serial No. 503,012, and in Great Britain June 5, 1930.

This invention relates to methods of, and apparatus for, annealing glassware and has particular relation to a method and apparatus of the general character disclosed in the patent to Mulholland No. 1,560,481, granted

Nov. 3, 1925.

In the employment of the apparatus or lehr disclosed in the above patent, the glassware is carried by an endless conveyor 10 through the lehr tunnel, wherein it is first subjected to a relatively high temperature to relieve the strains therein, and subsequently is gradually cooled as the ware approaches the exit end of the tunnel. The tunnel is 15 indirectly heated by a plurality of flues passing longitudinally therebeneath and to which hot gases of combustion are supplied from a fire box located beneath the forward portion of the lehr. The hot gases are drawn 20 through the flues by means of a suction fan which fan also may serve to draw cooling air through a cooling flue extending longitudinally above the tunnel.

Heat is generated in the fire box by means 25 of a burner located at one side thereof and discharging a flame into the interior thereof.

It is the general object of the present invention to provide an improved method of novel character, and novel apparatus for 30 supplying the hot gases of combustion to and distributing them in a lehr of the above character. In the above-described construction and in similar constructions, there is a strong tendency for the products of combustion to 35 travel through the firebox and into and through the flues in such a manner that the heating of the tunnel is non-uniform. This is particularly true where oil is used as the heating medium. Thus, one side of the tunnel 40 may be hotter than the other and the ware which passes through that portion of the lehr may be overheated to such an extent that imperfect annealing will result. Without special provision, it is practically impossible to control such non-uniform distribution of heat. On the other hand, where 45 different types of ware are being annealed at the same time, that is, ware of varying weight and/or thickness, the ware requiring the least heat may be overheated, and the

ware requiring the most heat may not be heated sufficiently, for proper annealing. This also is due to the fact that the distribution of heat in the firebox and flues cannot be sufficiently controlled.

55

Therefore, it is another object of the present invention to provide a novel method and novel apparatus whereby the lehr tunnel may be controllably heated uniformly where only a single type of ware is being annealed, or may be controllably heated non-uniformly when a plurality of types of ware requiring non-uniform temperature conditions are being passed through the tunnel, so that in any event, the ware is subjected to the proper temperature conditions for perfect annealing.

60

In attaining the above objects, a construction is provided which enables the combustion flame to be accurately positioned centrally of the firebox, to insure equalization of temperature conditions within the lehr tunnel itself which is heated by the gases of combustion which flow from the firebox into and through the tunnel heating flues. Thus for 70 a given type of ware, a substantially uniform temperature condition transversely of the lehr tunnel may be maintained. However, where different types of ware are being annealed, the combustion flame may be shifted 75 in a horizontal plane toward one side or the other of the firebox, as a result of which one side of the lehr tunnel is appropriately heated to greater extent than the other, according to the character of the different types of ware 80 passing respectively through the different parts of the tunnel.

85

In order that the invention may be readily understood, reference should be had to the accompanying drawings in which novel apparatus for practicing the novel method is employed.

90

In said drawings:

Figure 1 is a view in vertical longitudinal section of the front end portion of a glassware annealing lehr embodying the novel apparatus of the invention;

95

Fig. 2 is a view in horizontal section of the construction shown in Fig. 1 and taken on the line 2-2 of Fig. 1;

100

Fig. 3 is a view in transverse vertical section and rear elevation of the construction shown in Figs. 1 and 2 and taken substantially on the line 3—3 of Fig. 1; and

5 Fig. 4 is a detailed view of a part of the burner operating mechanism shown more completely in Figs. 1 and 2.

Referring in detail to the drawings, 5 designates generally a firebox having a combustion space 6 therein into which space a flame is introduced through a passageway 7 in the rear end of the firebox. At the entrance end of the passageway 7 are burner blocks 8 and 9 and a burner 10 which generates the flame 10 which is directed through the paths in the burner blocks and the passageway 7, into the combustion chamber 6.

The hot gases of combustion generated by the burner in the firebox, flow therefrom upwardly into the metallic flues 12 which extend longitudinally of the lehr tunnel (not shown), and which forms the bottom thereof. Such gases are introduced into the flues through a pair of ports or passageways 13 and 14 which lead upwardly to a throat casting 15 having separate passageways therein, one of which is shown at 16, Fig. 1.

In the construction shown, brick work indicated at 17 may be provided for blocking off the gases of combustion from the two innermost passageways (not shown) in the throat casting and hence from the corresponding innermost flues 12, so that the hot gases of combustion will be supplied only to the outermost flues to compensate for the dissipation of heat through the side walls of the lehr (Fig. 3) thereby equalizing the temperature conditions in the lehr tunnel. If desired, the brickwork 17 may be omitted or replaced by dampers in the passageways 16 for selectively controlling the passage of hot gases through the flues 12.

The hot gases of combustion conducted through the flues passes in good heat transferring relation to the glassware carried by an endless conveyor 18, which may be of reticulated construction and which is dragged along the top of the flues as clearly shown in Figs. 1 and 3.

50 Located centrally of the firebox and extending from the bottom to the top thereof is a baffle 19 which is positioned opposite the exit end of the passageway 7 and is provided with the inwardly diverging faces 20 which 55 serve to deflect the combustion flame toward the sides of the firebox. Opening into the bottom of the firebox between the baffle 19 and the passageway 7 is an air inlet port 21 to which diluting air is supplied through a 60 passageway 22 extending through the bottom of the firebox. The arrangement of the passageway 7, the air inlet port 21, and the baffle 19, is such that uniform and complete 65 mixture of the diluting air with the hot gases of the burner flame will be assured.

Considering now the operating means for the burner 10, it will be seen that the said burner is mounted upon a carriage 24 pivoted at 25 upon a slide 26 carried by rods 27. The rods 27 are positioned horizontally and extend across the rear or inner end of the 70 firebox, the ends thereof passing through suitable supports 28 and 29 connected to the frame work of the lehr structure.

The burner 10 being mounted for horizontal swinging movement on the slide 26, may be given such movement by means of a worm 30 engaging a segment gear 31 formed on the oscillatory carriage 24 for the burner. The worm 30 may be rotated by means of rod 32 connected by means of a universal joint or knuckle 33 to the worm 30, said rod being suitably journaled near its outer end in a bracket secured to support 28 and provided with a handwheel 34 as shown. The hand wheel 34 may be provided with a pointer 35 cooperating with a scale 36 for indicating the horizontal angular position of the burner. The rod 32 also may be employed for reciprocating the slide 26 on the rod 27 to slide the burner into and out of operative position and toward and away from the side of the firebox where it may be inspected, cleaned, and repaired. This is done by removing handwheel 34 from rod 32, and pushing rod 32 inwardly out of its bracket after which the burner support may freely be reciprocated on rods 27 by means of the rod 32.

In the employment of the novel apparatus above described, for carrying out the novel method of the invention, the burner 10 may be accurately positioned to direct a flame toward the center of the deflector or baffle 19 which, because of the presence of the diverging faces 20 thereof, serves to uniformly distribute the hot gases of combustion through the firebox and through the outermost flues 12 forming the bottom of the lehr tunnel. In other words, the hot gases of combustion are supplied in equal amounts to the outlet ports 13 and 14 of the firebox so that a substantially uniform temperature transverse to the lehr tunnel is maintained. If, however, different types of glassware are delivered to the opposite sides of the lehr tunnel, the burner 10 may be shifted about pivot 25 to direct the combustion flame to one side or the other, by the operation of the hand wheel 34, as a result of which the hot gases of combustion are supplied in appropriately unequal quantities to the ports 13 and 14 and to the outermost flues 12. Such distribution likewise is facilitated by the diverging faces 20 of the deflector 19, which as will be understood, also assist in the proper mixing of the combustion air supplied through the port 21 with the flame.

Thus it will be seen that the invention provides a novel method and novel apparatus

for controlling the temperature conditions in a lehr tunnel to secure proper annealing of the glassware delivered thereto, whether the glassware be of the same kind or of different kinds.

Having thus described my invention, what I desire to claim and to secure by Letters Patent is:

1. The method of annealing glassware which comprises passing such glassware through the tunnel of a lehr, directing a combustion flame into a firebox associated with the lehr, conducting the hot gases of combustion from the firebox into heat transferring relation to the glassware passing through the lehr, and laterally shifting the combustion flame to vary controllably the heat conditions in the lehr tunnel transversely thereof according to the character of the glassware 20 being annealed.

2. The method of annealing glassware which comprises passing said glassware through the tunnel of a lehr, directing a combustion flame into a firebox associated with the lehr, conducting hot gases of combustion from the firebox adjacent to the sides only of the lehr tunnel, and positioning the combustion flame relative to the firebox in such a manner as to supply controllably unequal 30 quantities of hot gases of combustion to the sides of the lehr tunnel.

3. Apparatus for annealing glassware comprising a lehr having a firebox associated therewith, a passageway formed in said firebox, a burner for directing a combustion flame through said passageway into said firebox, means for oscillating said burner in a horizontal plane to shift the combustion flame to one side or the other of the firebox, 40 a plurality of flues extending longitudinally of the lehr, passageways connecting the interior of the firebox to said flues, and a deflector located in said firebox opposite the inner end of said passageway for directing 45 said combustion flame into said passageways.

4. Apparatus for annealing glassware comprising a lehr, heating flues extending longitudinally of the lehr, a firebox associated with the forward portion of said lehr, a burner for directing a flame of combustion into the firebox, to generate gases of combustion therein, passageways leading from the firebox to said flues, and means for 50 horizontally oscillating the burner to regulate the quantities of gases of combustion supplied to said flues through said passageways.

5. Apparatus for annealing glassware comprising a lehr, heating flues extending longitudinally through the said lehr, a firebox, a burner for directing a flame of combustion into said firebox, passageways leading from said firebox to said flues, a deflector 60 positioned in said firebox against which said

flame impinges, said deflector having diverging surfaces, and an air inlet port in said firebox located between said deflector and said burner.

6. Apparatus for annealing glassware 70 comprising a lehr, heating flues extending longitudinally of said lehr, a firebox, a burner for directing a combustion flame into said firebox, a pivoted support for said burner, and means for swinging said support to horizontally oscillate said burner.

7. Apparatus for annealing glassware comprising a lehr, a firebox associated with said lehr, a burner for directing a flame of combustion into said firebox, means for horizontally swinging said burner about a pivot, and means for horizontally reciprocating 80 said burner transversely of the firebox.

Signed at London England this 3rd day of December 1930. 85

THOMAS WARDLEY.
